CULINARY SCRAPER OR SIMILAR ARTICLE

Paul A. Lawrence, 1660 Beaver Ave.,
Des Moines, Iowa 50310

Filed Apr. 27, 1970, Ser. No. 22,649

Term of patent 7 years

Int. Cl. D7—99

U.S. Cl. D44—1

Fig 1 is a top plan view of a culinary scraper showing my new design;

FIG. 2 is a bottom plan view;

FIG. 3 is a front elevational view;

FIG. 4 is a rear elevational view;

FIG. 5 is a left side elevational view;

FIG. 6 is a right side elevational view;

FIG. 7 is a top plan view of a culinary scraper showing another form of my new design;

FIG. 8 is a bottom plan view thereof;

FIG. 9 is a front elevational view;

FIG. 10 is a top plan view of a culinary scraper showing a third form of my new design;

FIG. 11 is a bottom plan view thereof; and

FIG. 12 is a front elevational view thereof.

I claim:

The ornamental design for a culinary scraper or similar article, substantially as shown and described.
